Attorney

UNITED STATES PATENT OFFICE.

GEORGE ERNEST PELTON, OF GEORGETOWN, KENTUCKY.

TYPE-WRITER.

1,324,265.

Specification of Letters Patent.

Patented Dec. 9, 1919.

Application filed June 20, 1919. Serial No. 305,699.

To all whom it may concern:

Be it known that I, GEORGE E. PELTON, a citizen of the United States, residing at Georgetown, in the county of Scott and State of Kentucky, have invented certain new and useful Improvements in Type-Writers, of which the following is a specification.

This invention relates to improvements in typewriters and more particularly to the ribbon mechanism thereof.

One of the objects of the present invention is to provide an improved ribbon mechanism whereby the full width of the ribbon may be utilized and it is designed more particularly as an improvement over the construction used in the Underwood machine and illustrated, for example, in patent to W. E. Barnard, No. 1,041,722, dated October 22, 20 1912.

A further object is to provide a simple and practical ribbon mechanism whereby the ribbon may be positioned with respect to the line of impact of the type so that when multicolored ribbons are being used in either entire red, entire black, or a combination of these colors appear in the impressions. If, however, a single colored ribbon is used then the full width of the ribbon may be employed.

These and other objects will be more apparent from the description hereinafter set forth when taken in connection with the accompanying sheet of drawing illustrating one of various possible embodiments of the invention. In this drawing Figure 1 illustrates in perspective such parts of the ribbon mechanism on an Underwood typewriter machine as is necessary to understand the invention, and showing the parts in position for utilizing one edge of the ribbon. Fig. 2 is a front elevation of a part of the ribbon shift mechanism in a different position, while Fig. 3 shows the same parts in a third position.

As is well known to those familiar with the typewriter art a ribbon guide 5 is actuated on the impression of each key to move vertically upward into the path of travel of the type bar whereby the ribbon indicated at 6 is interposed between the type and the paper at the instant of impact. This ribbon guide is pivotally mounted at 7 to one end of an arm 8 pivoted to the frame at 10 and actuated by a member 12 supported from a universal bar frame 13 whereby it moves

fore and aft with respect to the machine at each impression. This member 12 is of general U-shaped construction in horizontal cross-section, one arm of which is provided with a slot 14 in staggered relation with respect to an opposite slot 15.

Between these slotted arms is a member 17, as shown more clearly in Figs. 2 and 3, provided with a pin 18 at one side, adapted to coact with the slotted arm 14, while on the opposite side is a compound pin 20 provided with an offset extension 21 adapted to coact with the slot 15 in the position shown in Figs. 2 and 3, according to the extent of lateral movement given this member. This movement is accomplished by means of a link 22 connected at one end to the member 12, as shown in Fig. 1, while its opposite end is pivotally connected at 23 with an arm 24 mounted on a rock shaft 25. This rock shaft is provided at its forward end with the usual oscillating arm (not shown) which, when moved either to the right or left will cause a corresponding movement of the member 12. By moving this arm to half way position the parts occupy the relation shown in Fig. 3.

As the part 12 has a fore and aft horizontal movement and the part 17 is moved relatively vertically at each actuation of the universal bar, it will be seen that the throw given to the ribbon guide 5 is controlled by the engagement of the pins 18, 20 and 21 with the slots 14 and 15. Thus the pin 18 in engagement with the slot 14 will permit writing on one edge of the ribbon 6 while engagement of the pin 20 with the opposite slot controls the impressions upon the opposite edge. The pin 21 on the slot 15 however will insure the ribbon being engaged along a medial line, and in this manner the entire width of the ribbon may be utilized, thus diminishing the waste heretofore incident to typewriter ribbons when used on Underwood machines.

From the above it will be seen that the present invention provides a simple and practical device adapted to accomplish, among others, all of the objects and advantages herein set forth.

I claim:

1. In a mechanism of the character described, in combination, a ribbon guide, a universal bar associated therewith adapted to move the ribbon guide vertically at each actuation of the type, a pair of coacting

members interposed between the universal bar and ribbon guide whereby the extent of throw may be controlled to any one of three positions, one of said members being laterally shiftable and including a part having three portions, two oppositely projecting portions arranged in different horizontal planes, one of said portions having a third part lying in a still different horizontal plane whereby any one of said three portions may coact with slots in the other member to provide a different path of engagement between the type and the ribbon.

2. In a mechanism of the character described, in combination, a ribbon guide, a universal bar, intervening mechanism therebetween adapted to convey motion from the universal bar to the ribbon guide to interpose the ribbon between the type and the

platens, said mechanism including a slotted member associated with the universal bar, and a member provided with opposite and laterally projecting pins adapted to coact with the slots in said member, one of said pins having two parts lying in different horizontal planes, and means for moving the sliding member relatively to said pins whereby one or the other of said pins may be brought into engagement with the proper slot to control the path of impressions along any one of three desired portions of the ribbon.

In testimony whereof I affix my signature in the presence of two witnesses.

GEORGE ERNEST PELTON.
